UNITED STATES PATENT OFFICE.

RYNEER E. BROWN, OF HOLDENVILLE, OKLAHOMA, ASSIGNOR OF ONE-HALF TO
ALBERT STANLEY BAILEY, OF HOLDENVILLE, OKLAHOMA.

VALVE-SPRING LIFTER.

Application filed August 19, 1926. Serial No. 130,233.

This invention relates to an improved device, which is commonly known in the art as a valve spring lifter, the same being in the form of a novel tool for lifting a coiled spring such as is associated with a common form of internal combustion engine valve, the construction of the tool being such that the spring can be compressed and lifted to permit removal of the valve stem pin, whereby to facilitate disassembling or application of the engine valve. I am well aware of the fact that numerous tools have been patented and marketed to accomplish this result, but it is believed that the tool shown and specifically described in this application is an improvement upon prior devices of this kind, the same being composed of two parts, thus making it exceptionally simple in construction, and making it advantageous from the standpoint of the manufacturer, owing to the increased quantity of production and output, the ease of assembling, and compactness and convenience of parts.

The details and their association will become apparent from the following description and drawing:

In the accompanying drawing, forming a part of this application, and in which like numerals are employed to designate like parts throughout the same:

Figure 1 is a side view, with a portion broken away and shown in section, of a tool constructed in accordance with this invention, showing the manner in which it is used.

Figure 2 is a horizontal section, taken approximately upon the plane of the line 2-2 of Figure 1, and

Figure 3 is an end elevation of the valve spring engaging claw.

Referring to the drawings in detail, it will be seen that the reference character 1 designates a portion of an internal combustion engine cylinder block having valve openings and seats for cooperation with the usual valve. The valve here shown is of the mushroom type, and the head 2 is shown resting upon the valve seat and the stem 3 is shown extending downwardly through the usual guides. Surrounding the lower central portion of the stem is the coil spring 4 which has its lower end seated in a cup 5. Beneath this cup is a removable retaining pin 6. All of these parts are of the usual construction and constitute no part of the invention, but

serve to show the type of engine with which the tool may be used with facility.

The improved tool comprises a suspension member 7, which is here shown in the form of a flat metal bar, bent into C-shaped formation. The upper end terminates in a point 8 which is located at a point spaced beyond the lower downturned end 9. The point 8 is adapted to rest on the center of valve head 2, thus positioning the downturned end 8 at a point spaced from the valve mechanism. The lifting lever is connected to the downturned end 9, the lever comprising a part 10 of polygonal cross section, having a slot 11, with which the downturned end of the suspension member is pivoted, as indicated at 12. Formed on the outer end of this part 10 is a semicircular keeper 13, having downturned arms 14, disposed in spaced parallelism, these arms terminating in inwardly directed extremities 15, as shown better in Figure 3. With this arrangement, the keeper 13 partially surrounds the coil spring and disposes the arm 14 on diametrically opposite sides of the spring, and locates the inturned extremity 15 beneath the valve spring cup 5. Connected to the opposite end of the part 10 is a cylindrical portion which is bent upwardly as at 16, and bent again as at 17, to terminate in a hand grip or handle 18. The bend 17 is located about the vertical center of the C-shaped suspension member 7. The lower end portion of the handle however is bent on a line similar to that of the adjacent portion of the suspension member. These bends are particularly important in that they dispose the point of pressure at an elevation with respect to the suspension member to render the leverage comparatively powerful. Thus, a slight downward push upon the handle will serve to lift a comparatively sturdy coil spring with little or no exertion.

In practice, the pointed end 8 of the C-shaped member 7 is engaged with the head of the valve thus locating the lower end portion of this member at a point spaced away from the valve mechanism. This locates the lifting lever at a place to permit the claw to be readily engaged with the valve spring cup. Obviously, by forcing downwardly upon the handle 8, the lever will be rocked in a manner to lift the spring up and to permit ready removal of the valve stem

pin 6. A feature in this arrangement is that the device may be located in position without regard to the exactness in location usually required in tools of this kind. In fact, the device may be swung from one side to the other to swing the handle out of the way of interfering objects, thus rendering the tool exceptionally easy to manipulate.

It is believed that by considering the description in connection with the drawings, persons familiar with tools of this kind will be able to obtain a clear understanding of the same. Therefore, a more lengthy description is thought unnecessary.

15. I claim:

A valve spring lifter comprising a substantially C-shaped suspension member hav-

ing a pointed end at its top adapted to rest upon a valve head, the opposite end of the member terminating in a downturned extremity, and said extremity being located at a point spaced from a line extending in alignment with the first named end, an operating lever pivotally connected at a point between its ends to the downturned extremity of said suspension member, said lever having means on its outer end for engaging a valve spring cup, the opposite end of the lever being directed upwardly, and terminating on a plane opposite the central portion of said C-shaped suspension member.

In testimony whereof I affix my signature.

RYNEER E. BROWN.
